(57) **CLAIM**

The ornamental design for a sock, as shown and described.

DESCRIPTION

FIG. 1 is a first perspective view of a first embodiment of a sock.

FIG. 2 is a second perspective view thereof.

FIG. 3 is a front view thereof.

FIG. 4 is a right side view thereof.

FIG. 5 is a top view thereof.

FIG. 6 is a bottom view thereof.

FIG. 7 is a first perspective view of a second embodiment of the sock.

FIG. 8 is a second perspective view thereof.

FIG. 9 is a front view thereof.

FIG. 10 is a right side view thereof.

FIG. 11 is a top view thereof; and,

FIG. 12 is a bottom view thereof.

The hatching of the first embodiment of the sock indicates a contrasting color or material relative to the remainder of the sock.

1 Claim, 12 Drawing Sheets
